UNITED STATES PATENT OFFICE

CLARENCE V. FUQUA, OF KANSAS CITY, MISSOURI, ASSIGNOR TO THE CLEANERS EQUIPMENT CORPORATION, OF KANSAS CITY, MISSOURI, A CORPORATION OF MISSOURI

BATCH RENOVATOR

Application filed October 13, 1927. Serial No. 225,985.

My invention relates to cleaning apparatus and more particularly to a device for purifying a liquid used in cleaning operations, the object of the invention being to provide a 5 compact and easily installed apparatus wherein the liquid may be purified by saponification and by a water bath and having improved means of renovation by these processes.

10 In accomplishing these objects I have provided improved details of structure, the preferred forms of which are illustrated in the accompanying drawings, wherein:

15 Fig. 1 is a detail view, partly broken away, of an apparatus constructed according to my invention.

Fig. 2 is a vertical transverse section of the apparatus.

20 Fig. 3 is a vertical longitudinal section on the line 3—3, Fig. 2.

Referring in detail to the drawings:

25 1 designates a cabinet having the front wall 2, the shortened rear wall 3, the side walls 4, the bottom 5 inclined as shown and producing the sump 6 between the front wall and the bottom, the cabinet being supported on legs 7 which are extensions of angle irons whereby the corners of the structure are reinforced. The cabinet is constructed preferably of sheet steel and the joints welded.

30 The front and rear walls are substantially longer than the side walls in the preferred form so that the cabinet is substantially wider than its length from front to back, for purposes which will be disclosed.

35 A division wall 8 is installed as shown parallel with the side walls in the process of construction of the cabinet, whereby two chambers are produced in the cabinet, the first chamber 9, which is the smaller of the two, being designated a saponifying chamber and the second, 10 being designated a water rinse chamber. An emulsifying or saponification substance is deposited in the saponification chamber 9, the substance designated 11 occupying a prescribed space in the chamber. A top plate 12 is provided for the cabinet in which is a port 13 through which filtering or saponifying materials may be deposited in the saponification chamber. Vents 14 and

15 are provided in the top plate for the two chambers, the vents being connected by the pipe 16 and leading to the outside through the coupling 17.

55 A supply line 18 from a source not shown delivers the cleaning fluid which is to be renovated or purified, through a coupling 19 into a slit pipe 20 having the longitudinal slot 21, the valve being positioned adjacent the bottom of the saponification chamber for 60 delivery of the cleaning fluid into the cabinet for renovation. A steam pipe 22 controlled by the valve 23 is also introduced into the slotted inlet 20 for cleaning the inlet pipe and for cleaning the filtering material 65 when desired.

70 The fluid passing into the first chamber through the slotted inlet percolates upwardly through the filtering material to the top of the chamber and there is conducted out of the chamber and into the adjacent water rinse chamber through the pipe 24, the end of which is sealed in an opening of the division wall, and which extends to the bottom of the water rinse chamber where a slotted tube 25 is connected therewith for 75 delivery of the fluid conducted from the saponification chamber, in sheet form into the water rinse chamber.

80 I provide an opening 26 with suitable fittings 27 in the side wall of the tank for access to the water rinse chamber at substantially the level to which water is to be deposited and maintained in the chamber. The water level is designated as 28 to indicate 85 the relation and to suggest the purposes of the opening 26 which will be again referred to.

90 In the same side wall of the cabinet and serving the water rinse chamber are ports 29, 30 and 31, any one of which may be provided with the outlet pipe 32 for conducting the fluid that is passed through the cabinet away therefrom to service. The openings not so used may be closed by plugs 33 or all 95 of the openings may be coupled together and valves used to throw the desired ports into service.

100 I further provide an opening 34 in the side wall bounding the saponifying chamber,

and having the appropriate fitting 35 including a pipe 36 and a valve 37, the fitting being positioned adjacent the upper level of the filtering material, for access to the interior of the tank adjacent said upper level.

The fluid is understood to flow continuously through the cabinet from the saponifying chamber to the rinse chamber and out therefrom either to storage or back to use, the fluid being delivered to the cabinet in foul condition.

Suspension of flow of fluid and pressure into the cabinet may set up suction to draw the fluid that is in the cabinet out therefrom, through the inlet, and to meet this contingency I provide an anti-siphon valve 38 in a connection 39 between the supply line 18 and the vent coupling 16.

A gauge glass 40 of a type which will be more particularly described elsewhere is installed in the front wall of the cabinet, having branches 41 and 42 respectively above and below the upper surface of the filtering material in the saponifying chamber to give information on the height and condition of the fluid and mixtures in this chamber. A similar gauge device 43 is installed in the front wall of the cabinet and in position to give information of the condition of the liquids in the lower part of the rinse cabinet, particularly to show the elevation of the water in the chamber. A third gauge 44 is positioned in the front wall of the cabinet adjacent the upper portion of the rinse chamber to disclose the height and condition of the cleansed fluid adjacent the point of emergence from the renovating and purifying apparatus. The gauge glasses shown and preferably installed are of a type more particularly described and novel features claimed as invention in an application filed of even date herewith.

Suitable drains 45 and 46 properly valved are provided at the lower point of each chamber for withdrawal of the substances in the chambers, as desired.

The structure having been provided as described, the fluid that has been used in cleaning garments or the like is delivered through the slotted inlet to the filtering material in the saponifying chamber. The material is preferably an emulsifying agent such as an alkali which, reacting with the greasy substances carried by the fluid, produces a soapy substance that forms a filtering scum adjacent the surface of the filtering material. The liquid is physically filtered through this scum and the emulsifying factor for withdrawal of impurities, and the physical filtering factor, substantially cleanse the fluid. The waste material gathers in substantial quantities adjacent the surface of the filtering material and excess accumulation of emulsified greases and oils would tend to settle down into the filtering

material and seriously hamper the passage of the fluid therethrough and prevent contact of the fluid with the saponifying material. It is to meet this objectionable condition that opening 34 is provided where-through the emulsified greases and oils may be removed as desired and as they accumulate. The steam port 22 may be used to admit steam or like agent through the slotted inlet to soften the scum and the emulsified materials to promote their withdrawal through said opening 34, the steam or other cleansing agent introduced also cleansing the filtering material to render it more effective. The water of steam condensed in use will find its natural level either adjacent the surface of the filtering material, from which it may be withdrawn through the opening 34; or at the bottom of the chamber, from which it may be withdrawn through a drain 45.

The fluid thus separated from the greasy substances and other foreign matter acted on by the filtering material, rises to the top of the saponifying chamber, is received by the round tube opening of the conductor 24, and is conducted to the bottom of the water rinse chamber and admitted from the slotted tube in a sheet which travels in thin and substantially extended form through the water, thus receiving a rinse or washing whereby further cleaning of the liquid is accomplished.

The fluid having been projected into the rinse chamber in the thin sheet form mentioned, and passing through the water, enters the space above the water in a stream having a considerable cross section, and then travels through a considerable space and over an appreciable lapse of time between the surface of the water and the outlet from the chamber so that opportunity is given for the settling down of light lints, silts and water solubles to the surface of the water, where the settling tend to remain intact. The said settling or waste may be removed through the port 27. Such foreign matter as may be captured by the water, and fall there-through, may be removed; and water and fluid may be drained out, through the drain 46 in the bottom of the rinse chamber.

The structure as thus provided and operating is particularly adaptable for use in smaller plants where a compact apparatus is desired and where more exact control of each factor in the cleansing of the liquid and in the movement of the liquid from machines through the renovating process and back to the machines, are required.

What I claim and desire to secure by Letters Patent is:

1. In apparatus of the character described, a tank including side and end walls and a partition parallel with the side walls dividing the tank into chambers for containing purifying materials adapted to be maintained

at predetermined levels therein, a horizontal liquid inlet tube extending through one side wall of the tank into one chamber adjacent the bottom thereof and below the position of the purifying material therein, and a vertical pipe communicating with the upper end of said chamber and having a horizontal discharge portion located adjacent the bottom of the other of said chambers for gravity transfer of liquid from the first to the second of said chambers, opposite side walls having valved ports at the positions of the upper levels of the purifying materials in the chambers.

15. 2. A batch renovator comprising a casing having a bottom inclined downwardly from the rear to the front wall thereof, a vertical partition sealingly dividing the casing into a saponification chamber and a water rinse chamber, a horizontal inlet pipe extending transversely in the saponification chamber adjacent the front and bottom walls thereof, a conduit having an inlet end mounted in the partition adjacent the upper edge thereof and adjacent the rear wall of the casing, an outlet member on said conduit extending horizontally in the second chamber adjacent the front and bottom walls thereof, and an outlet pipe communicating with the water rinse chamber adjacent the upper end thereof.

30. 3. In a batch renovator, a casing including an inclined bottom forming a sump and a partition having a lower edge engaged with said bottom forming a saponification compartment and a water rinse compartment adapted to contain respectively a filtering agent and a rinsing agent having predetermined levels, valved pipes communicating with said chambers at the positions of said predetermined levels adapted for introducing said agents to the chambers, a slotted horizontal inlet pipe located in said sump in the first named chamber, a conduit communicating with the first named chamber and having an outlet end portion located in the sump in the second chamber and means for leading off liquid from the second chamber.

In testimony whereof I affix my signature.
CLARENCE V. FUQUA.
